UNITED STATES PATENT OFFICE.

WILLIAM A. CHRYST, OF DAYTON, OHIO, ASSIGNOR TO THE DAYTON ENGINEERING LABORATORIES COMPANY, OF DAYTON, OHIO, A CORPORATION OF OHIO.

DYNAMO-BRUSH RIGGING.

Application filed July 15, 1922. Serial No. 575,217.

This invention relates to dynamo-electric machines employed to start internal-combustion engines and then to generate current for ignition, lights, and charging a battery. The principal objects of the present invention are to promote the dependability and life of a dynamo-electric-machine employed on internal-combustion engines and more especially, to provide improved mountings and adjustments for the brushes which permit inspection and repair or replacement of these parts with a minimum disassembling of the apparatus.

In the drawings:

Fig. 1 is an end view of a dynamo-electric-machine provided with the present invention;

Fig. 2 is a plan view of the ground brushes of the commutators;

Fig. 3 is a transverse sectional view on line 3—3 of Fig. 4;

Fig. 4 is a longitudinal sectional view;

Fig. 5 is a sectional view on line 5—5 of Fig. 4;

Fig. 6 is an inside view of one of the end frames of the dynamo; and

Fig. 7 is a sectional view on line 7—7 of Fig. 6.

Referring to the drawings, the dynamo-electric-machine is formed with a continuous annular field frame 38 adapted to be attached to an engine crank case 30 by a depending flange 39 and bolts 40. Field pole 41 is formed integral with the frame 38 and upper pole shoe 42 attached to the pole by bolt 43. Field coils 70 and 72 surround the pole 41 above the shoe. 45 is lower pole shoe formed integral with the lower portion of field frame 38. Side walls of the field frame are made relatively thin to reduce to a minimum the width of the dynamo-electric-machine. The right end wall 47 of the field frame 38 is formed integrally with the frame and is made relatively thick to provide the quantity of metal required in addition to the metal in the side walls 46, for providing an adequate flux path from the field pole 41 to the lower pole shoe 45.

The left end housing of the dynamo-electric-machine is formed by an end frame 48 and a cover 49 completely separated along a diagonal line 50 to one side of the axis of the armature 51. This armature is supported by a ball bearing 52 secured in an opening in the right end wall 47 of the

field frame, and by ball bearing 53 secured in an aperture in the left end frame 48. Left bearing 53 is secured permanently in position by side plates 54, 55 held against the inner and outer faces respectively of the end housing member 48, by rivets 56. The end frame 48 is preferably held in position during operation of the dynamo-electric-machine and during repair or adjustment of the brushes by relatively heavy bolts 57 which are set tightly in tapped holes in the left end of field frame 38 so that it will be difficult to loosen these bolts with an ordinary screw driver or pincers. The cover plate 49 is held in position preferably by a smaller bolt 58 which may be readily turned with pincers or a screw driver to remove this section of the rear end housing.

It has been found that this construction promotes uniform operation and lengthens the life of a dynamo-electric-machine, for the bolts 57 may be set at the factory or a garage with heavier tools than are generally available to the automobile driver, and the driver usually will not remove the larger rear end housing 48, which carries the rear end bearing 53 of the armature. The armature will be supported in operable position, except when the car is taken to a garage. This prolongs the life of the bearings and insures proper alignment of the armature shaft with the moving parts cooperating therewith.

Armature 51 is provided with relatively heavy windings connected with commutator 62 and with relatively fine windings connected with commutator 63. The heavy armature windings cooperate with series field winding 70 when the dynamo functions as a motor, and the fine armature windings with shunt field 72, when the machine functions as a generator.

65 is a metal plate extending across the left end of the field frame 38 above the armature (Figs. 3 and 4) and held in position by bolts 66 passing through the plate into bosses 67 formed on the field frame. This plate supports binding post 68 connecting cable 69 in the electrical system (not shown) with the series winding 70; post 71 connected to one end of the shunt winding 72 and post 73 connected by lead 74 from the generator lifting brush 75. On the left-hand side of plate 65 (Fig. 3) is a stud shaft 76 connected on the inner side

of plate 65 with the other end of series field winding 70 and carrying on the front side of the plate a bell crank lever 77. These posts and the stud shaft are insulated from plate 65. Bell crank lever 77 has a relatively long arm 78 supporting lifting motor brush 79, a shorter substantially vertical arm 80 supporting a circumferentially grooved fibre roller 81 and a still shorter downwardly projecting arm 82 supporting a roller 83 adapted to be engaged by the conical inner end of control rod 88 (Fig. 1) which functions to lift the brush 79 from the motor commutator. Screw 84 has a downwardly projecting end 85 which slides in a groove in rod 88 to guide the latter. Rod 88 extends through hole 88^a in frame 48 and is operated by a pedal (not shown).

Encircling the stud shaft 76 on the rear side of the bell crank lever 77 is a relatively stiff coiled spring 89 one of whose ends 90 engages a stud projecting from the plate 65, the other end of the coil spring 89 engaging a lug 92 on the brush arm 78 and tending to hold the brush 79 in engagement with the motor commutator 62. This construction holds the brush 79 against the upper surface of the motor commutator where the brush is accessible when end plate 49 is removed and provides for movement of the brush 79 to control operation of the dynamo-electric-machine as a motor.

Referring to Figs. 1, 3 and 6, the lower right-hand surface 93 of end frame 48 is provided with a relatively large opening 94 adjacent the line of separation 50 between the two members 48 and 49. Ground brush supporting plate 95 is bolted to the outer side of frames 48 against the surface 93 thereof in position to cover the opening 94. Riveted to the inner surface of plate 95 is an L-shaped bracket 96 having a web 97 projecting inwardly toward the axis of the armature. 98 is a stud shaft projecting to the left in Fig. 4, and supported by the web 97 and in turn supporting brush arm 99, normally held inwardly against the generator commutator 63 by coiled spring 100 encircling the brush arm hub 101 located between the web 97 and brush arm 99. One end 102 of the spring engages a lug 103 formed on the arm 99 and the other end 104 engages a stud 105 carried by the web 97. 106 is a generator ground brush supported on the free end of arm 99 and held against the generator commutator 63 by the spring 100.

Mounted on the opposite side of the web 97 and projecting toward the field frame 38 is a stud shaft 107 supporting brush arm 108 carrying on its outer end a motor ground brush 109 normally held against the motor commutator 62 by coiled spring 110 which encircles the brush arm hub 111 located between the web 97 and the arm 108. One end

112 of the spring engages a lug 113 formed on brush arm 108 and the other end 114 of the spring engages a stud 115 carried by the web 97.

Ground brush supporting plate 95 is easily detached from the dynamo-electric-machine to permit inspection or repair without disassembling other parts of the machine. It has been found that the mounting of the supporting plate 95 as shown facilitates assembly of the ground brushes with the commutator and securing the supporting plate in position by providing for a movement of the plate substantially radially toward the commutator to bring the brushes and plate into final position.

Referring to Figs. 6 and 7 there is provided between the ball bearing retainer plate 55 and the inner surface of the housing member 48 an annular recess 116 in which is located the hub of a rotatable plate 117 carrying a radial ear 118 insulatingly supporting a transverse stud shaft 119. Mounted on shaft 119 is a brush arm hub 120 and third brush arm 121 connected with the hub and supporting a generator regulating third brush 122. Coiled spring 123 encircling the hub 120 holds the third brush against commutator 63. One end 124 of the coiled spring engages a lug 125 formed on the brush arm 121, and the other end 126 of the spring engages a non-conducting stud 127 attached to the ear 118. This brush is normally located within end housing member 48 beneath the bell crank lever 77 supporting the motor lifting brush 79 (Fig. 3) and is connected to one end of generator winding 72 by lead 128. Diametrically opposite the stud shaft 119 supporting third brush 122 the rotatable plate 117 is formed with an ear 129 having an arcuate slot 130 and the inner retaining plate 55 of the ball bearing 53 is formed with an ear 131. Screw 132 projects through the arcuate slot in ear 129 and is threaded into ear 131 to clamp the two ears together and hold the rotatable plate 117 and the third brush 122 carried by it in adjusted position relative to the generator commutator. The ears 129 and 131 and bolt 132 project outwardly from housing member 48 to a point enclosed by end housing member 49 (Figs. 3 and 6). Upon removal of the smaller bolt 58 the housing member 49 can be detached exposing the adjusting screw 132 which may be loosened to permit adjustment of the third brush on its commutator; or this screw may be removed to permit rotation of the third brush to a position outside of the housing member 48 thus permitting repair or replacement of the third brush without removing the member 48. Cotter pin 133 encircling third brush lead 128 and passing through a side wall of the housing member 48 normally holds the slack portion of this lead away from moving parts but permits adjustment

125
129
130

of the third brush and rotation thereof to a position adjacent the oblique edge of housing 48 as described. Finger piece 134 formed on the ear 129 assists in rotating the third brush when making adjustments.

5 Inner retaining plate 55 of the ball bearing 53 is also provided with an ear 135 supporting an inwardly projecting stud shaft 136 upon which is rotatably mounted a bell 10 crank 140 having a brush arm 141 carrying 15 on its free end generator lifting brush 75. Brush arm hub 143 holds brush arm 141 in spaced relation to the supporting ear 135 and coil spring 144 encircling the hub normally holds the brush against the generator 20 commutator, the spring 144 having an end 144^a bearing against the lug 141^a of lever arm 141, and an end 144^b bearing against a non-conducting stud 144^c carried by the 25 plate 55. The other arm 141^a of the bell crank lever 140 carries a stud 145 on which is pivotally mounted a link 146 having a notched outer end 147 engaging the grooved roller 81 carried by arm 80 of the bell crank lever 77 which supports motor lifting brush 79.

Referring to Fig. 3 the length of the link 146 is so proportioned that when the roller 83 is released and spring 89 forces motor lifting brush 79 against the motor commutator 62 the link 146 acting on the bell crank lever 140 will raise generator lifting brush about $\frac{1}{16}$ of an inch from generator commutator 63, the spring 89 being made 30 stronger than spring 144 so that it will move both brushes 79 and 75 against the action of spring 144 which tends to seat generator lifting brush 75. The notch in the free end of lever 146 is made relatively deep to provide a lost motion connection between bell 35 crank lever 77 and bell crank lever 140 so that when the roller 83 is elevated, motor lifting brush 79 will be raised a relatively long distance from its commutator while, 40 when the roller 83 is released, the spring 89, acting through the bell crank lever 77, link 146, and bell crank lever 140, will raise generator lifting brush 75 a short distance from its commutator.

50 Referring to Fig. 4, 147 is a right end housing on a dynamo-electric-machine enclosing an over-running clutch whose inner element 148 is fastened to the right end of the armature shaft 149. The outer clutch 55 element 150 is adapted to be driven by an engine, not shown. On the inner wall of the gear housing 147 is packing cup 152 which prevents heavy grease within the gear housing from working through the ball bearing 52 to the inside of the field frame. The outer end of the gear housing 147 is provided with an enclosure 153 of sheet metal having a central aperture through which the engine shaft projects.

55 The type of internal-combustion engine

starting and electrical generating system for which the present invention is particularly adapted is disclosed in patents to Kettering and Chryst, #1,250,188 and #1,303,831. The mode of operating the present

70 dynamo in such a system is briefly as follows: The closing of the engine ignition switch causes the dynamo generator brushes 75, 122 and 106, and the shunt field winding 72, to be connected with a storage battery, 75 whereupon the dynamo operates as a shunt-wound motor to turn slowly the gear 160 attached to its shaft 149. By means of end-wise movable intermediate gearing, the gear 160 may be connected with the engine fly-wheel gear. The intermediate gearing is 80 moved by a pedal-operated device which also operates the control rod 88 having a conical end which engages the roller 83, shown in Fig. 3. Normally the intermediate 85 gearing is out of engagement with the engine gear and gear 160, and the brush 79 is maintained out of engagement with the commutator 62. Operation of the pedal will first cause the intermediate gearing 90 to engage the gear 160; and then, while being slowly rotated, the intermediate gearing will be meshed with the engine gear. When the intermediate gearing is substantially in mesh with the engine gear, the roller 83 will be released to permit the brush 79 to engage the motor commutator 62 and the brush 75 to be lifted from the generator 95 commutator 63. The dynamo will then operate as a motor with torque sufficient 100 to crank the engine. Release of the pedal will restore the brushes 75 and 79 to normal as shown in Fig. 3, so that the dynamo may operate as a shunt generator. The overrunning clutch members 148 and 150 permit the 105 dynamo to overrun the connection with the engine at the clutch member 150, while cranking; and an overrunning clutch in the intermediate gearing allows the engine to overrun the gear 160 in case the latter is 110 still in mesh with the intermediate gear after the engine becomes self-operative. As this system is well-known to those skilled in the art, illustration thereof is deemed 115 unnecessary. This electrical system is mentioned merely as showing one use of the present invention which is clearly susceptible of other uses.

One of the advantages of the present invention is in the accessibility of the device 120 for adjusting the third or dynamo regulating brush 122. After the end housing member 49 has been removed, the screw 132 and the handle 134, which are outside the diagonal edge of the end housing 48, are readily 125 accessible.

Another important advantage is that all of the dynamo brushes can be removed without removing the end housing 48. This is 130 important because the installation of the

4
dynamo upon the frame of the engine may be such that the end housing 48 could not be removed without first removing other parts mounted upon the engine or chassis.

5 6. It will be understood that the dynamo is adapted to be attached to the engine frame with its left side, as viewed in Figs. 1 and 3, adjacent the engine, the right side being accessible. After removing housing cover

10 49, it is obvious that brush 79 can be removed. Since link 146 may be detached from roller 80 while the latter remains in place, the brush arm 141 can be rotated clockwise until the screw 75^a holding brush

15 75 is accessible. Brushes 106 and 109 can be removed from their brush arms after removing the plate 95 from the housing 48. After removing screw 132 from plate 55, plate 117 can be rotated counter-clockwise, 20 as viewed in Fig. 3, until the screw 122^a holding brush 122 is accessible from the right side of the dynamo.

25 While the form of embodiment of the invention as herein described, constitutes a preferred form, it is to be understood that other forms might be adopted, all coming within the scope of the claims which follow.

What is claimed is as follows:

30 1. A dynamo including a commutator, a frame member providing a housing for the commutator and having a single continuous opening through one side thereof, brushes within the housing some of which are normally inaccessible through the opening, 35 brush supporting means permitting all of the brushes to be removed through said opening, said means including a plate covering part of the opening, and carrying certain brushes, and a cover for the remainder 40 of the opening.

45 2. A bipolar dynamo having a commutator, a field frame provided with a pole piece extending vertically from its armature, an end frame attached to the field frame and providing a housing for the commutator, 50 said frame having a single opening through one side thereof and extending substantially from the top to the bottom of the machine, brushes engaging the commutator approximately vertically thereof, and brush supporting devices permitting removal of said

brushes through said opening while the frame remains assembled, said devices including a plate covering one end of the opening and supporting certain brushes. 55

3. A dynamo having commutators and brushes, a brush and commutator housing frame having an opening in one side thereof, and means for producing movement of one brush radially relative to the 60 commutator by movement of the other, said means permitting movement of one brush independently of the others to a position when the brush is accessible for removal from the dynamo, the frame remaining assembled. 65

4. A dynamo having a plurality of commutators, an armature having windings connected with the commutators, and a plurality of brushes cooperating with each 70 commutator, said dynamo being an assembly of a subassembly including the field frame, the armature and a dynamo brush, a subassembly including a plurality of brushes and an end frame adapted to be attached to the field frame and providing for the commutator and brushes a housing having an opening through which the brushes may be manipulated and a subassembly including a cover for the opening 75 in said housing and plurality of brushes supported by the cover. 80

5. A dynamo having an armature provided with windings for motoring and for generating purposes, respectively, commutators adjacent one end of the armature and connected with the armature windings, said dynamo being an assembly of a subassembly including a field frame and brush adapted to be moved into and out of engagement with one of the commutators, and a subassembly including an end frame and the other dynamo brushes one of which is movable into and out of engagement with the other of the commutators, said last mentioned subassembly including means for detachably connecting said movable brushes whereby motion of one brush will cause motion of the other brush. 95

In testimony whereof I hereto affix my 100 signature.

WILLIAM A. CHRYST.
